UNITED STATES PATENT OFFICE.

ANGELO PERRI, OF HAVERHILL, MASSACHUSETTS, ASSIGNOR TO UNITED SHOE MACHINERY COMPANY, OF PATERSON, NEW JERSEY, A CORPORATION OF NEW JERSEY.

PULLING-OVER MACHINE.

1,249,185.

Specification of Letters Patent.

Patented Dec. 4, 1917.

Application filed May 2, 1913. Serial No. 765,057.

To all whom it may concern:

Be it known that I, ANGELO PERRI, a citizen of the United States, residing at Haverhill, in the county of Essex and State of Massachusetts, have invented certain Improvements in Pulling-Over Machines, of which the following description, in connection with the accompanying drawings, is a specification, like reference characters on the drawings indicating like parts in the several figures.

This invention relates to shoe supporting means for pulling-over and other upper stretching or shaping machines and is herein shown as embodied in supporting means for a pulling-over machine such as is shown in United States Letters Patent No. 1,029,387, granted June 11, 1912 on an application of Ronald F. McFeely.

An object of this invention, among others, is to provide last supporting means which will contribute to the operation performed by these machines of shaping the upper to the last. As herein shown, the last supporting means embodying this invention serves this purpose by engaging the upper on the top of the forepart of a shoe at opposite sides of the middle portion of the shoe and moving to stretch the portion of upper located between the engaging points. It also serves the upper shaping purpose by engaging the upper on the top of the forepart of a last at or near the middle of the last and forcing the upper against the last in the hollow or depression which is usually found between the instep and the toe of the last, particularly if the last has a high toe or prominent toe. In both of these ways this invention assists in overcoming the very common difficulty experienced by the upper bridging across this depression from the instep to the toe. This invention may be embodied in mechanism which operates to shape the upper either by pressure or by stretching in the way above indicated as well as in such mechanism as that herein shown which operates to shape the upper in both of these ways.

An important feature of this invention consists in last supporting devices arranged to engage the top of the forepart of a shoe and to be moved apart in response to last supporting pressure for stretching the stock that is located between them, or it may be by

movement produced automatically or otherwise after they have contacted with the shoe and before they come into firm last supporting relation to the work.

Another feature of this invention consists in a last support and means for moving it into a position opposite to the top of the last and then for moving it into supporting engagement with the work.

These and other features of the invention will appear and be more fully understood in connection with the following description of a preferred embodiment of the invention and will then be pointed out in the claims.

Referring to the accompanying drawings, Figure 1 is a view, partly in elevation and partly in section, of so much of a pulling-over machine of the type shown in said prior Letters Patent as is necessary for illustrating this invention.

Fig. 2 is a similar view of the parts shown in the lower portion of Fig. 1 showing the changed relation of the parts brought about as the operation of the machine progresses.

Fig. 3 is a side elevation of the toe portion of a shoe being pulled over illustrating the manner in which the upper bridges between the instep of the last and a high toe.

The sole rest 2 and its operating mechanism, the grippers 4 and their operating mechanism, and the tackers 5 and their operating mechanism are or may be the same as shown and described in said patent, as may also be the general construction of the side clamp arms 6 and the operating mechanism therefor. The rubber covered side clamp blocks 8 are mounted to adjust themselves angularly to the requirements of individual shoes, but have no yielding movement outwardly upon the arms 6 such as they usually have heretofore had.

The last supporters are carried by slides 10 which are guided for horizontal movement in blocks 12 secured rigidly to the side clamp arms 6. A spring 13 holds each slide 100 pressed inwardly toward the median line of the machine. Each last supporter 20 is mounted on a carrier 15 which is pivoted to the slide 10 to swing about a substantially horizontal axis and rests upon the inner end of a lever 16 which is pivoted to the block 12 and can turn about an axis located at 17 but is normally held with its inner end upraised

by means of a spring 18. An adjustable stop screw 19 carried by the lever and abutting against the block 12 provides means for variably determining the position in which the 5 spring 18 will normally hold the lever 16 and the carrier 15. Each last supporter 20 is pivotally connected, preferably by a universal joint, near its inner edge to the carrier 15 and the last supporter is acted upon near 10 its outer edge by a spring-pressed plunger 22 by which it is normally held in the angular position shown in Fig. 1.

In the operation of the machine the cycle of which may be in general as set forth in 15 said prior patent, the arms 6 are moved toward each other for clamping the upper and upholding the shoe for the upper securing tacks to be inserted after the grippers have given place to the tackers 5. As the arms 6 20 move toward each other the adjacent end faces of the carriers 15 engage one another, the last supporters 20 being at such time located below the shoe and out of touch therewith and each in the angular position 25 represented in Fig. 1. After such engagement of the carriers 15 with one another they yield with relation to the blocks 12 against the resistance of the springs 13. The lower faces of the carriers 15 are inclined as 30 shown whereby said carriers constitute in effect wedges located between the front arms of the levers 16 and the last supporters 20 and, therefore, as the carriers yield outwardly in the blocks 12 they are forced upwardly, moving about their pivotal connections with the slides 10 and therefore carrying the last supporters 20 apart as they rise and engage the shoe. Also by this wedging 35 action the last supporters are made to engage the shoe while occupying the angular positions shewn in Fig. 1. As the movement is continued and the upward pressure becomes harder, the spring plungers 22 yield and each last supporter tips outwardly away 40 from the other, moving about its pivotal connection with the carrier 15 in the direction indicated by the lower arrows in Fig. 2. By the upward movement of the last supporters against the shoe they press the upper into 45 engagement with the last at the place where the upper is most likely to bridge between the instep and the toe of the last, particularly if it is a high-toed last. During the described pivotal movement of the last supporters in the direction indicated by the 50 lower arrows in Fig. 2 they rub or stretch the upper toward opposite sides of the last as indicated by the arrows on the last in Fig. 2, thus supplementing the action of the grippers which preferably are at this time still 55 pulling upon the upper. In these ways the last supporters coöperate with the grippers to conform the upper to the last and tighten the upper to a very substantial extent. 60 65 When the last supporters are turned into the

position shown in Fig. 2 and the carriers 15 can be moved no farther upwardly, the supporting levers 16 thereafter yield against the action of their springs 18 to permit the side clamp arms 6 to continue and complete 70 their stroke for bringing the clamp blocks 8 into engagement with the shoe at the edge of the last bottom. It is to be noted that the upper tightening action of the last supporters takes place prior to the engagement 75 of the clamping blocks 8 with the shoe and therefore at a time when the grippers may, without interference from the clamping blocks 8, take up any slack stock produced by the action of the last supporters. The 80 parts are shown in Fig. 2 with the clamping blocks just engaging the shoe. In the completion of the movement of the arms 6, said blocks will be made to clamp the upper firmly to the sides of the last after which 85 the incoming tackers 5 will trip the grippers and cause the wipers located on the lower faces of the tackers to lay the upper into position to be tacked. It will be noted that the supporting connections for the last 90 supporters 20 are so arranged as to afford a substantially rigid upholding of the shoe against the impact of the tack drivers.

Having explained the nature of the invention and described a preferred embodiment thereof, I claim as new and desire to secure by Letters Patent of the United States:—

1. A pulling-over machine having, in combination, last supporters arranged to engage the lower face of the forepart of an inverted shoe upon opposite sides of the median line of the shoe, and operating mechanism for causing said last supporters to move each away from the other for stretching the stock 100 which is located between them.

2. A pulling-over machine having, in combination, last supporters, and operating mechanism for moving them laterally of a shoe on a last to positions opposite to the top of the forepart of the shoe and out of touch with the shoe and then moving them in a different direction into supporting contact with said shoe.

3. A pulling-over machine having, in combination, last supporters, and operating mechanism for positioning them under the forepart of an inverted shoe, then moving them upwardly into supporting contact with said shoe, and thereafter moving them apart in engagement with the shoe for stretching the stock that is located between them.

4. A pulling-over machine having, in combination, last supporters, and operating mechanism arranged to move said last supporters upwardly into engagement with the lower face of the forepart of an inverted shoe and arranged to direct such movement of each last supporter obliquely outwardly toward the adjacent side of the shoe whereby 125 130

the engagement of the last supporters with the upper serves to stretch the portion of upper located between them.

5. A pulling-over machine having, in combination, last supporters arranged to engage the lower face of the forepart of an inverted shoe upon opposite sides of the median line of the shoe, carriers upon which the last supporters are mounted, operating means for 10 moving the carriers first in the direction to position the last supporters under the shoe and then in the direction to move said last supporters upwardly into contact with the shoe, and mountings for the carriers arranged to direct such upward movement of the last supporters outwardly toward the opposite sides of the shoe for stretching the upper.

6. A pulling-over machine having, in combination, side clamp arms movable toward the median line of the machine, and last supporting means movably mounted on said arms and arranged to be abutted against one another as the side clamp arms close and 25 then to be automatically raised into engagement with the shoe by the continued movement of the arms.

7. A pulling-over machine having, in combination, side clamp arms movable toward the median line of the machine, and last supporting means movably mounted on said arms and arranged to be abutted against one another as the side clamp arms close and then to be automatically raised into engagement with the shoe by the continued movement of the arms, said means having provision for causing the supporting faces which engage the shoe upper to be moved toward opposite edges of the last for stretching the upper after they engage it.

8. A pulling-over machine having, in combination, side clamp arms movable toward the median line of the machine, a slide mounted in each arm to yield outwardly, 45 last support carriers pivoted on the slides and arranged to abut together under the shoe when the side clamp arms are closed, and means for causing said carriers to be automatically lifted toward the shoe after 50 they have abutted.

9. A pulling-over machine having, in combination, side clamp arms movable toward the median line of the machine, a slide mounted in each arm to yield outwardly, 55 last support carriers pivoted on said slides and arranged to abut together under the shoe as the side clamp arms are closed and to yield outwardly relatively to the arms during the completion of the closing movement of said arms, and wedging means for 60 raising the last support carriers as they yield outwardly in the side clamp arms.

10. A pulling-over machine having, in combination, side clamp arms movable toward the median line of the machine, a slide

mounted in each arm to yield outwardly, last support carriers pivoted on said slides and arranged to abut together under the shoe as the side clamp arms are closed and to yield outwardly relatively to the arms 70 during the completion of the closing movement of said arms, wedging means for raising the last support carriers as they yield outwardly in the side clamp arms, and springs associated with said wedging means 75 to permit the said clamp arms to complete their strokes after the last supporters have engaged the shoe and can be moved no farther.

11. A pulling-over machine having, in combination, last supporters arranged to engage the lower face of the forepart of an inverted shoe upon opposite sides of the middle portion of the shoe, and carriers by which said last supporters are raised into 80 engagement with the shoe, the last supporters being normally inclined toward each other and being movable automatically responsive to engagement with the shoe and in directions to stretch the portion of stock located between them.

12. A pulling-over machine having, in combination, last supporters arranged to engage the lower face of the forepart of an inverted shoe upon opposite sides of the middle portion of the shoe, carriers by which said last supporters are raised into engagement with the shoe, said last supporters being pivotally mounted on the carriers, and means yieldingly holding said supporters 95 tipped toward each other and permitting the supporters to tip away from each other as they are pressed in engagement with the shoe.

13. A pulling-over machine having, in combination, last supporters adapted to engage the lower face of the forepart of an inverted shoe, carrying means by which said supporters are moved into engagement with the shoe and upon which each supporter is 100 pivoted near its edge which is adjacent to the other supporter, and means which normally tips the supporters toward each other and permits them to turn about their pivots away from each other in a direction to 110 stretch the stock located between them when they are forced into engagement with the shoe.

14. A pulling-over machine having, in combination, carriers, last supporters and 120 side clamps arranged on the carriers for the last supporters to engage the shoe before the side clamps engage it and to yield while the side clamps come into contact with the shoe; and means to cause said last supporters to move, after engaging the shoe and before the side clamps engage it, in a direction to 125 tighten the upper toward the edge of the last.

15. A pulling-over machine having, in 130

combination, a rest for the sole bottom against which the bottom of the shoe is held for the pulling operation, last supporters movable into operative positions below and 5 adjacent to the median line of the shoe in position to press against the last a portion of the shoe upper which is bridged between the instep and the toe of the last, and means for operating said last supporters to so press 10 the bridged portion of the upper into engagement with the last.

16. A pulling-over machine having, in combination, last supporters arranged to engage a shoe at the top of the forepart in 15 position to press a bridged portion of the upper extending from the instep to the toe into engagement with the last, said supports being relatively movable to conform to the shape of the last, and automatic means for 20 positioning and operating said last supporters to do their work.

17. A pulling-over machine having, in combination, last supporters arranged to engage a shoe at the top of the forepart in 25 position to press a bridged portion of the upper extending from the instep to the toe into engagement with the last, and automatic means for positioning said last supporters and for operating them so to press 30 the bridged portion of the upper and to tighten it outwardly in opposite directions from the median line of the last.

18. A pulling-over machine having, in combination, movably mounted last supporters and operating means for moving them from opposite directions laterally under the shoe, stopping them when properly positioned, and then raising them into supporting engagement with the shoe.

40 19. In a pulling-over machine, a side clamp arm, a horizontal slide therein, a last supporter movably connected to said slide, means to swing the arm, means to stop said supporter under the shoe while the arm continues to move relatively to it and the slide, and a wedge for raising the supporter during 45 such continued movement.

20. In a pulling-over machine, a side clamp arm, a last supporter mounted to be 50 carried into operative position under the shoe by said arm, means to swing the arm, means to stop the inward movement of the supporter while the arm continues to move, and a wedge actuated by such continued 55 movement of the arm to raise the supporter against the shoe.

21. In a pulling-over machine, a side clamp arm, a last supporter mounted to be carried into operative position under the 60 shoe by said arm, means to move the arm, means to stop the inward movement of the supporter while the arm continues to move, and connections actuated by such continued 65 movement of the arm for imparting to the shoe engaging face of the last supporter

an upward and slightly outward movement, substantially as described.

22. A machine for use in making shoes having, in combination, means arranged for pressure applying engagement with the sole face of a shoe, means for working the upper toward and over the sole face of the shoe, and means for supporting the shoe against displacement by pressure applied to the sole face thereof and including a support mounted at one lateral side of the shoe and movable laterally to a position adjacent to the top face of the shoe and then substantially perpendicularly to the top face of the shoe 70 into supporting engagement with said top face of the shoe. 75

23. A machine for use in making shoes having, in combination, means arranged for pressure applying engagement with the sole face of a shoe, means for working the upper toward and over the sole face of the shoe, means for supporting the shoe against displacement by pressure applied to the sole face thereof and including a support mounted at one lateral side of the shoe, and mechanism operating in time relation to the movement of the pressure applying means to shift the support first laterally to a position adjacent to the top face of the shoe and then toward said top face of the shoe 80 into position to support the shoe. 85

24. A machine of the class described having, in combination, shoe supporting members arranged to engage the forepart of the shoe upper, supporting means for said members constructed and arranged to cause said members to be moved in directions outward toward the sides of the shoe by pressure of the members against the shoe, and means for effecting relative movement of the shoe and 100 said supporting members to cause the members to be moved in said directions. 105

25. A machine of the class described having, in combination, shoe supporting members arranged to engage the top of the forepart of the shoe upper on opposite sides of the median line of the shoe, supporting means upon which said members are mounted for swinging movement in directions outward toward the sides of the shoe, and yielding means tending to swing said members toward each other while permitting their outward swinging movement in response to pressure against the shoe. 110 115

26. A machine of the class described having, in combination, shoe supporting members arranged to engage the top of the forepart of the shoe upper, supporting means for said members movable to carry them laterally of the shoe into positions opposite to the top of the forepart, said members being mounted on their supporting means for movement outward in opposite directions toward the sides of the shoe in response to pressure against the shoe, and means for 120 125 130

effecting relative movement of the shoe and said supporting means to cause said outward movement of the members.

27. A machine of the class described having, in combination, shoe supporting members arranged to engage the top of the forepart of the shoe upper on a last upon opposite sides of the median line of the shoe, and means for effecting relative movement of 10 said members and the shoe to cause said members to stretch the upper outwardly toward the sides of the shoe.

28. A machine of the class described having, in combination, last supporting members arranged to engage the top of the forepart of a shoe on the last in position to press

a bridged portion of the upper extending from the instep to the toe into engagement with the last, said members being movable laterally of the shoe to an initial position 20 opposite to the top of the forepart, and means for moving said members from said initial position toward the shoe to cause them to perform their function.

In testimony whereof I have signed my 25 name to this specification in the presence of two subscribing witnesses.

ANGELO PERRI.
